United States Patent Office

Des. 196,555
Patented Oct. 8, 1963

196,555

FOUNTAIN

Jack E. Lake, Griggs-Midway Bldg., St. Paul, Minn.

Filed Sept. 10, 1962, Ser. No. 71,627

Term of patent 14 years

(Cl. D91—4)

Fig. 1

Fig. 2

Fig. 3

Fig. 4

FIG. 1 is a side elevational view of a fountain embodying my new design;

FIG. 2 is a top plan view of the fountain of FIG. 1;

FIG. 3 is an end elevational view of the fountain of FIG. 1; and

FIG. 4 is a rear elevational view of the fountain of FIG. 1.

I claim:

The ornamental design for a fountain, substantially as shown.
